UNITED STATES PATENT OFFICE.

JOSEPH M. MAYLEAS, OF NEW YORK, N. Y.

HAT CONSTRUCTION.

1,412,479.

Specification of Letters Patent. Patented Apr. 11, 1922.

Application filed June 10, 1921. Serial No. 476,462.

To all whom it may concern:

Be it known that I, JOSEPH M. MAYLEAS, a citizen of Latvia, and a resident of the city of New York, borough of Manhattan, in the 5 county and State of New York, have invented a new and Improved Hat Construction, of which the following is a full, clear, and exact description.

This invention relates to hat constructions, 10 and has for an object the provision of a new and improved double or cushion brim for hats, which brim can be very simply, efficiently and economically manufactured with considerable saving in material over the old 15 method of making brims for hats of the type to which this invention appertains.

Another object resides in the provision of a brim construction, with special reference to a double brim which can be readily manufactured and associated with a cover of some 20 suitable fabric of the nature of plush or felt or other fabric having a minimum amount of seam, whereby the appearance of the hat is greatly improved.

25 A further object resides in the provision of a brim in which the outer edge is rolled over or blocked in a smooth curve and in which the cover fabric on the edge presents a smooth, finished appearance on the lower 30 surface of the brim as well as on the upper.

A still further object resides in the provision of means whereby the cover for the brim may be placed on with a minimum amount of labor and a minimum likelihood 35 of the formation of wrinkles by stretching the cover on the frame.

The invention is illustrated in the drawings, of which—

Figure 1 is a partial vertical section through 40 a hat;

Figure 2 is an inverted plan view of the brim;

Figure 3 is a view of the body portion of 45 the brim at one stage in the process of its manufacture;

Figure 4 is a view of the body portion of the brim at a later stage in its manufacture; and

Figure 5 is a detail view illustrating the 50 manner of forming the seam in the covering material for the brim.

As shown in the drawings, the preferred form of the invention is illustrated as being in the form of a lady's hat, preferably a hat

covered with plush. This hat may have a 55 body portion or crown 1 of any desired shape, covered preferably with plush and provided with the usual band 2 as well as the usual lining 3. It is customary in the construction of hats of this and similar forms 60 to turn the inner edges of the brim upward as shown at 4 and to suitably fasten the upturned edges 4 between the lower ends of the crown and the lining.

In accordance with my invention, the brim 65 shown in the drawings is formed of any material suitable for making brims, such as buckram, which is cut out in the proper shape initially, as shown in Fig. 3, with central apertures 5 and up-turned flange portions 6 70 and 6' surrounding these apertures. The main portion of the brim is made of a sheet of fabric bent over to form a double layer 7 and 8 joined together by a smooth, curved rim portion 9 and spaced apart excepting at 75 their inner edges 9' and 10, which are later, when the hat is assembled, drawn close together. This form of the brim body portion, as shown in Fig. 3, is made over any suitable forming mandrel or block, as is customary in 80 this industry. After thus being formed, the lower flange 6' is cut off, as shown in Fig. 4, leaving the upper flange 6 intact. While still on the block this brim body or backing is 85 covered with a layer of plush or similar material. This sheet of covering material for the brim is joined by a seam which, as shown in Fig. 5 by the numeral 11, is cut on the bias so as to permit the material to be stretched smoothly and evenly over the 90 curved brim body portion without the formation of wrinkles.

In Fig. 2 I show in dotted lines the substantially radially extending seam 12 formed between the adjacent edges of the fabric or body portion of the rim, and which edges may be suitably connected together as by sewing or gluing. After the covering of plush or other material is placed over the brim, it, during this process, has assumed the 95 shape shown in Fig. 1 in which the layers 7 and 8 are most widely spaced apart at the rim and then gradually approach each other at their inner ends. As mentioned above, the up-turned edges of the plush and the flange 100 6 are disposed between the lower ends of the lining and the crown and are suitably connected therebetween.

In this manner I provide a new and improved brim construction which is light, flexible, and in which the edge of the brim presents a smooth, finished appearance, 5 forming a thick curved surface over which the plush or similar material covering the brim body may be stretched in a smooth and finished manner hitherto impossible. This 10 brim also provides that the covering material of one piece may extend smoothly over the under surface as well as over the upper surface.

It will thus be manifest that I have provided a hat which has a stiff foundation of buckram or the like and which may be provided with a cloth covering of any suitable material, and further, that the brim is essentially a cushion brim as known in the art at this time, the same being of tubular or 15 channel shaped cross section to produce the hollow or shell-like formation as described with a hollow empty interior chamber or void, and which results in a single piece brim having a longitudinally seamless and relatively thick edge or rim, that is, without longitudinal or circumferential seams extending around the rim or outer edge thereof, as is usual in the art. By cushion brim, 20 is meant a brim having an upper brim and a lower brim and edge or a top, a facing and an edge which is formed of a foundation of stiffening material such as buckram and a cloth covering, both the foundation and the covering being folded in the middle 25 or equi-distantly between the opposite edges of the band or ring into which the strip forming the same is made, so that the same can be made each of a single piece of material with the facing, edge and top continuous, thereby producing a circumferentially 30 seamless edge which may be shaped in any suitable manner by blocking and stretching as is common in the art. The brim in the form shown is thicker at the outer edge or 35 rim than at the inner edge, so as to taper inwardly or increase in thickness outwardly, as regards the cross section of the brim.

In the old method of making hats of the type or style to which this invention appertains, separate upper and lower pieces are used to make the foundation or stiffening and separate upper and lower rectangular pieces are used to form the covering including the top and facing, while the edge or 40 edging at the rim is formed with or consists of a joint or seam as a result of the edges of the material being brought together. The pieces are pasted together and blocked, thus requiring the centers and corners to be cut 45 off to fit the head and produce the desired shape, and the material at the edge or rim is folded or wired so that a seam is produced with a brim having a relatively flat cross section. With the present construction and improved method of making hats and hat brims 50

in particular, the foundation is made from a single section or band and so is the covering, as hereinbefore set forth, the two being simultaneously blocked and stretched into shape, so as to produce a cushion and double 55 brim without longitudinal seams or stitches and of hollow tubular cross-section and empty to form a void within, the top and bottom portions being spaced apart and disconnected at the inside and the edge or rim 60 shaped as desired, but essentially seamless irrespective of its shape cross sectionally. Thus, the foundation or stiffening and the covering, and so the brim as an entirety produced therefrom is continuous from the base 65 of the crown at the headsize over the top, edge and facing and back to the crown, the inner edges or portions of the brim top and facing being brought together and in contact for association with and attachment to 70 the crown at the base and the lining. It should be noted that in addition to being of hollow tubular form to produce a brim with the top and bottom portions spaced apart and disconnected at the inside between the outer 75 and inner edges, either by stitches, paste or otherwise, and with the foundation or stiffening, and the covering similarly shaped, each is smoothly and continuously extended over the top, edge and bottom cross sectionally of the brim and of inwardly tapered, 80 streamline, wedge shaped or doubly convex cross-section, thereby presenting a thick outer edge or rim and an attractive and pleasing soft cushion appearance. 90

What I claim is:

1. A hat having a hollow cushion brim, said brim comprising a strip having its ends connected to form a band, said band having a stiffening medium extending throughout 105 its entire area, portions at each side of the medial line between the opposite edges of said band being brought toward each other in inwardly convergent relation to form a hollow flexible cushion brim with a relatively thick rim and a single interior void. 110

2. A hat brim comprising a covering and a stiffening medium for and carried by the same and extending throughout the entire area thereof, the brim being devoid of filling and the material of the brim extending continuously over the top, rim and bottom radially in folded hollow relation. 115

3. A hat having a brim comprising a covering band folded at the rim, a stiffening attached to said covering and following the contour thereof, said brim being hollow within the stiffening to form when the band is folded, upper and under brims spaced apart and having no connection therebetween 120 through the thickness of the brim between the rim and the inner edge, and the rim being free of seams running around the same circumferentially. 125

4. A hat comprising a crown and a brim, 130

5 said brim comprising a stiffened reinforced covering, the stiffening and covering being folded to extend continuously over the top, edge and bottom of the brim, with an interior empty chamber within the covering and stiffening.

10 5. A brim having a buckram foundation of hollow tubular form and a covering secured over the same, the material of the foundation and the covering each extending continuously over the top edge and bottom of the brim.

15 6. A brim having a foundation of wedge-shaped cross section and devoid of filling, and a covering fastened smoothly against the foundation, the material of the foundation and the covering each consisting of a strip cut on the bias and joined at its ends to form a band and the material of the foundation and 20 covering extending continuously and in one piece formation over the top, edge and facing of the brim except where the ends are joined together, and the top and facing being spaced apart from the inner to the outer 25 edge.

30 7. A cushion brim comprising a body of relatively stiff material bent over on itself at the rim in hollow formation and a covering secured in conforming relation thereto adhesively over the top, rim and bottom, the rim being free of stitches connecting the top and bottom and also free of seams running around the rim longitudinally, said brim tapering in thickness from the rim to 35 the inner edge where attached to the crown.

40 8. A hat comprising a crown and a brim attached thereto at the base, said brim comprising a stiffening foundation body of buckram or the like shaped into rebent tubular form with a thick edge and spaced upper and under brim portions unconnected between the rim and inner edge and approaching each other toward the inner edge and a covering secured to the foundation body and 45 smoothly conforming thereto.

50 9. A hat brim of hollow tubular formation, said brim being formed of a single section of material cut on the bias joined at its ends to produce a band, said brim being free of seams extending around its circumferential edge.

55 10. A hat brim with an edge devoid of longitudinal seams consisting of a strip of material having its ends joined to form a band, and a foundation therefor, said material and foundation being continuous from the inner edge of the top and over the rim of the brim to the inner edge of the facing in a radial direction to present a seamless 60 formation longitudinally and radially except at the ends of the strip joined to form the band.

65 11. A hat construction comprising a brim formed of a single sheet of material having a lining of stiffening material bent upon

itself to form spaced upper and lower layers of material and a relatively thick edge at the rim, the layers being spaced apart at the rim and approaching each other toward their inner edges, said rim being smooth, and a covering of plush or similar material stretched over said brim and secured in conforming relation thereto.

70 12. A hat brim construction comprising a body portion shaped in the form of a hollow brim, a covering of plush or other fabric therefor, said covering and body portion consisting each of a band having its ends joined together to form a seam and the seam of the covering extending at an angle to the radius of the brim.

75 13. A hat having a brim consisting of a foundation and a covering, the foundation and covering each consisting of a single band folded equi-distantly between the opposite edges thereof in substantially U-shaped formation, the covering being secured on the foundation and both attached to a crown, the material forming the top, facing and edge of the brim extending continuously and uninterruptedly from the inner edge of the top over the rim edge of the brim and to the inner edge of the facing, the rim being hollow and forming an empty chamber within.

80 14. A method of making hat brims consisting in blocking and stretching a band of covering material having a reinforcing and stiffening medium into substantially channel-shaped cross section to form a closed rim and spaced inner edges for attachment to a crown.

85 15. A method of hat construction consisting in taking a foundation of stiffening material in the form of a band and blocking the same into substantially U-shaped channeled formation continuous from one inner edge to the other inner edge, at least one inner edge being provided with a flange extending substantially at right angles thereto to form the head size for attachment to a crown, and covering said foundation.

90 16. A method of hat construction consisting in taking a foundation of stiffening material in the form of a band and blocking the same into substantially U-shaped channeled formation continuous from one inner edge to the other inner edge, at least one inner edge being provided with a flange extending substantially at right angles thereto to form the head size, covering said foundation and securing the covering in conformity thereto, the covering consisting of a similar band with the material also extending continuously from edge to edge, the rim being smooth, and connecting a crown to the brim through the medium of the flange and covering.

95 17. A method of making hat brims consisting in cutting strips of buckram and cloth or other covering material, sewing the

ends thereof together to form bands and blocking the same in folded or U-shaped form in cross-section and stretching the covering over the foundation produced by the 5 buckram.

18. A method of making hat brims consisting in forming bands of foundation material and covering material cut on the bias, blocking the same in folded form and 10 stretching the covering snugly and smoothly over the foundation, the material being continuous over the top, rim and facing, and the opposite edges of the material being

formed into flanges one of which is the head size.

19. A method of making brims for hats of the class described consisting in blocking a band of buckram into substantially U-shaped cross section with a covering band of cloth thereover, the opposite edges being brought in proximity to each other and forming outturned flanges, severing one of said flanges, and securing the covering and other flange to the inside of a crown at the base portion thereof.

JOSEPH M. MAYLEAS.
